Assistant Examiner — Aula Soroush

(57) CLAIM

The ornamental design for a breast pump funnel, as shown and described.

DESCRIPTION

FIG. 1 is a front elevational view showing the first embodiment of my design;

FIG. 2 is a front perspective view thereof;

FIG. 3 is a rear elevational view thereof;

FIG. 4 is a right side elevational view thereof;

FIG. 5 is a left side elevational view thereof;

FIG. 6 is a top perspective view thereof;

FIG. 7 is a bottom perspective view thereof;

FIG. 8 is a perspective view showing the second embodiment of my design;

FIG. 9 is a front perspective view thereof;

FIG. 10 is a rear perspective view thereof;

FIG. 11 is a right side elevational view thereof;

FIG. 12 is a left side elevational view thereof;

FIG. 13 is a top perspective view thereof; and,

FIG. 14 is a bottom perspective view thereof.

The broken lines illustrate a portion of the breast pump funnel and form no part of the claimed design.
